(57) **CLAIM**

The ornamental design for a handle section of a tool, as shown and described.

DESCRIPTION

FIG. 1 is a perspective view of our design for a handle section of a tool;

FIG. 2 is a top view thereof;

FIG. 3 is a bottom view thereof;

FIG. 4 is a left side view thereof;

FIG. 5 is a right side view thereof; and,

FIG. 6 is a sectional view thereof at cross-section VI-VI of FIG. 2.

The portion of the tool shown in broken lines are environmental only and form no part of the claimed design.

1 Claim, 4 Drawing Sheets

FIG. 2

FIG. 3

FIG. 4

FIG. 5

FIG. 6
